(57) **CLAIM**

I claim the ornamental design for a modular wine rack, as shown and described.

DESCRIPTION

FIG. 1 is a top perspective view of a modular wine rack.

FIG. 2 is a bottom perspective view thereof.

FIG. 3 is a left side elevation view thereof.

FIG. 4 is a front elevation view thereof.

FIG. 5 is a right side elevation view thereof.

FIG. 6 is a back side elevation view thereof.

FIG. 7 is a top plan view thereof.

FIG. 8 is a bottom plan view thereof.

FIG. 9 is an enlarged detail thereof of area 9 within FIG. 4.

FIG. 10 is an enlarged detail thereof of area 10 within FIG. 6; and,

FIG. 11 is a top perspective exploded view thereof.

The dash-dot-dot lines in FIGS. 4, 6, 9, and 10 depict the boundaries of the areas of the details and form no part of the claimed design.

1 Claim, 9 Drawing Sheets
